UNITED STATES PATENT OFFICE.

DAVID A. JENKINS, OF RYE VALLEY, OREGON.

WASHING-MACHINE.

1,185,101.

Specification of Letters Patent. Patented May 30, 1916.

Application filed December 11, 1915. Serial No. 66,394.

To all whom it may concern:

Be it known that I, DAVID A. JENKINS, a citizen of the United States, residing at Rye Valley, in the county of Baker and State of Oregon, have invented certain new and useful Improvements in Washing-Machines; and I do hereby declare the following to be a full, clear, and exact description of the invention, such as will enable others skilled in the art to which it appertains to make and use the same.

The invention relates to improvements in washing machines.

The object of the present invention is to improve the construction of washing machines and to provide a simple, inexpensive and efficient washing machine of strong and durable construction capable of rapidly and thoroughly washing clothes without injuring the fabrics by wearing or tearing the same.

A further object of the invention is to provide a washing machine equipped with a rotary drum or cylinder and relative rotary rollers for operating on the clothes and having means for preventing the small pieces from wrapping around the rollers that are carried by the rotary drum or cylinder.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from the spirit or sacrificing any of the advantages of the invention.

In the drawings Figure 1 is a longitudinal sectional view of a washing machine constructed in accordance with this invention, the rotary drum or cylinder being shown in elevation. Fig. 2 is a longitudinal sectional view of the same through the rotary drum or cylinder. Fig. 3 is a central transverse sectional view. Fig. 4 is a transverse sectional view of one end of the machine illustrating the arrangement of the concentric arcuate inner and outer racks and the pinions of the rollers. Fig. 5 is a transverse sectional view showing one end of the rotary drum or cylinder in elevation. Fig. 6 is a transverse sectional view through the other end of the washing machine illustrating

the arrangement of the gearing for rotating the drum or cylinder.

Like numerals of reference designate corresponding parts in the several figures of the drawings.

In the accompanying drawings in which is illustrated the preferred embodiment of the invention, the body of the washing machine which consists of a suitable receptacle 6 sides 1 and a curved bottom 2 formed integral with the sides. The end walls 3 are preferably constructed of wood and are rounded at the bottom to conform to the configuration of the curved bottom 2 of the body but the washing machine body may be constructed in any other desired manner as will be readily understood.

The washing machine body is provided at opposite sides with longitudinal boards or pieces 4 secured at their ends to the end walls of the washing machine body at the side edges thereof and provided with supporting legs 5. This construction provides a simple, efficient and inexpensive frame of the washing machine body and supporting of the same.

Within the washing machine body is mounted a rotary drum or cylinder 6 adapted to contain the clothes and other fabric to be washed and provided at its periphery with a door 7 to afford access to its interior and equipped at intervals around its periphery with rotary rollers 8 which are rotated by the means hereinafter described during the rotary movement of the drum or cylinder for rubbing the clothes and thereby washing the same. The rotary drum or cylinder is provided at one end or head 9 with a journal 10 arranged in an open bearing 11 of the adjacent end of the washing machine body and provided with an attaching plate 12 suitably secured to the exterior of the head 9 of the rotary drum or cylinder. The other head or end of the rotary drum or cylinder is provided with a plate 13 having a socket 14 preferably of triangular form for the reception of a triangular shaft 15 but any other polygonal configuration may of course be employed.

The shaft 15 which has a rounded bearing portion 16 is removably journaled in one end of the washing machine body and it is adapted to be withdrawn from the socket 14 of the plate 13 to enable the rotary drum or cylinder to be removed. Mounted upon the

polygonal portion of the shaft 15 is a gear wheel 17 which meshes with a pinion 18 of an operating shaft 19 journaled on the adjacent end of the washing machine body 5 and located above the shaft 16 and equipped with an exterior crank handle 20 by means of which the operating shaft is rotated for the drum or cylinder but any other suitable operating means may of course be employed 10 and instead of operating the washing machine by hand a suitable power may be used.

The rollers 8 are journaled in suitable bearings in the head of the rotary drum or cylinder and the journals 21 at one end of 15 the rollers are equipped with pinions 22 which are arranged to mesh with inner and outer arcuate concentric racks 23 and 24 arranged in parallelism and spaced apart to provide a passage for the pinion 22. The 20 inner and outer racks which are secured to the adjacent ends of the washing machine body at the bottom portion thereof are located at intervals so that the rollers in passing between the racks alternately engage the 25 inner and outer portions thereof and are reversely rotated to cause small articles wrapping around the rollers to be unwrapped therefrom so that there will be no liability of small pieces clogging and interfering with the operation of the washing 30 machine whereby the efficiency of the same is materially increased. The rollers and the rotary drum or cylinder are provided with perforations 26 and 27 and the rotary drum or cylinder is provided at its periphery with longitudinally disposed buckets 28 consisting of strips or pieces preferably dished or concaved at one face to provide longitudinal recesses for carrying the water upwardly to discharge the latter upon the 40 rotary drum or cylinder at the top thereof. The ends of the cylinder or drum are also provided with perforations 29 to permit the water to flow freely into and out of the said 45 cylinder or drum.

It will be seen that the washing machine which is simple and comparatively inexpensive in construction is adapted to thoroughly and uniformly wash the clothes which are 50 carried around with the cylinder and acted on by the rollers and that the rollers are positively rotated in reverse direction periodically while at the bottom portion of the washing machine and when in contact with 55 the clothes and other fabric being washed.

Also it will be clear that the reversal of the rotation of the rollers will prevent fabrics from winding around them so that the rollers will be kept clean and free and a maximum efficiency of the machine insured. 60

What is claimed is:—

1. A washing machine of the class described including a body, a rotary cylinder or drum mounted within the body and 65 adapted to receive the clothes to be washed, rollers carried by the drum or cylinder at the periphery thereof and projecting into the same to engage the clothes, and means for reversely rotating the rollers to change 70 the direction of rotation of the rollers periodically to prevent fabrics from wrapping around the same.

2. A washing machine of the class described including a body, a rotary cylinder 75 or drum mounted within the body and adapted to receive the clothes to be washed, rollers carried by the drum or cylinder at the periphery thereof and projecting into the same to engage the clothes, pinions connected with the rollers and rack bars arranged to mesh with the pinions.

3. A washing machine of the class described including a body, a rotary cylinder or drum mounted within the body and 85 adapted to receive the clothes to be washed, rollers carried by the drum or cylinder at the periphery thereof and projecting into the same to engage the clothes, pinions connected with the rollers and inner and outer 90 rack bars arranged to alternately mesh with the said pinion.

4. A washing machine of the class described including a body, a rotary cylinder or drum mounted within the body and 95 adapted to receive the clothes to be washed, rollers carried by the drum or cylinder at the periphery thereof and projecting into the same to engage the clothes, pinions connected with the rollers and inner and outer 100 concentric rack bars located at the bottom portion of the washing machine and arranged to mesh alternately with the pinions for reversely rotating the rollers.

In testimony whereof I affix my signature 105 in presence of two witnesses.

DAVID A. JENKINS.
